UNITED STATES PATENT OFFICE.

WILLIAM T. BARRATT, OF BENNINGTON, VERMONT.

STOP MOTION FOR KNITTING MACHINES.

Application filed November 18, 1921. Serial No. 516,040.

To all whom it may concern:

Be it known that I, WILLIAM T. BARRATT, a citizen of the United States, residing at Bennington, in the county of Bennington and State of Vermont, have invented new and useful Improvements in Stop Motions for Knitting Machines, of which the following is a specification.

This invention relates to improvements in stop motion mechanisms for machines in which a strand or strands of yarn are employed in the manufacture of fabric.

The particular embodiment of my invention hereinafter set forth in the specification and embodied in the claims is especially adapted for use in connection with knitting machines.

The object of the invention is to provide a stop mechanism which will stop the machine when the yarn fed into the machine is subjected to excess tension or undue strain, as for example, when the strand of yarn becomes knotted or has kinks or enlargements therein, said stop motion mechanism being adapted to operate to stop the machine under such conditions.

The object of the invention is particularly to provide a very sensitive stop motion, whereby a machine employing the lightest and frailest kinds of yarn may be stopped when said yarn is not operating properly and is subjected to a tension whereby the same becomes broken.

Another object of the invention is to provide means whereby a plurality of yarn guiding mechanisms may be simultaneously thrown into and out of operative position.

Another object of the invention is to provide means for regulating the tension on the yarn by means of the yarn guides.

Other objects and desirable results to be obtained will be more fully hereinafter set forth in the specification.

The invention consists particularly in the yarn guide mechanism which is very delicately positioned and adjusted to operate to actuate the stop motion mechanism when the yarn breaks or when the tension on the yarn for any reason becomes slack or fails altogether.

This invention is in some respects similar to the invention patented by me No. 1,173,244, patented February 29, 1916 and No. 1,186,645, patented June 13, 1916, in so far as the particular mechanism for stopping the rotation of the shaft is concerned and

the rotary and normally stationary stop members, but differs from the said inventions embodied in said Letters Patent in the means which guides the thread and which operates to stop the rotary stop member. As in said Letters Patent the present invention contemplates as one embodiment thereof a clutch mechanism which is thrown out of operation by a stop mechanism, whereupon a brake is applied to stop the machine quickly and said stop mechanism embodies a rotary stop member and a normally stationary stop member which is movable toward and away from the rotary stop member. The normally stationary stop member has thereon a rock shaft which is provided with a pair of arms, one of which carries a yarn guide, the other of which is adapted when the tension on the yarn slackens, or when the yarn breaks, to drop between and into interlocking engagement with said rotary and stationary stops, whereupon the rotation of the shaft of the rotary stop member is stopped and thereupon the stop mechanism is actuated to throw out the clutch.

To these ends and others hereinafter appearing in the specification, the invention consists in the combination and arrangement of parts set forth in the following specification and particularly pointed out in the claims.

Referring to the drawings:

Figure 1 is a sectional plan of my improved stop mechanism.

Fig. 2 is a sectional elevation taken on the line 2—2 of Figure 1.

Fig. 3 is an enlarged plan view of the particularly novel part of my invention.

Fig. 4 is a sectional elevation taken on the line 4—4 of Figure 3.

Fig. 5 is a detail front elevation of the yarn guide stop mechanism.

Fig. 6 is an enlarged detail section of the frictional device for the counterweight.

Like numerals refer to like parts throughout the several views of the drawings.

In the drawings, 10 is the frame of the machine. 11 is the main driving shaft. 12 is a pulley forming one member of a clutch and 13 is the other member of said clutch. 14 is a rock shaft having an arm 15 thereon which engages the clutch member 13 to throw the same into or out of engagement with said clutch pulley 12. 16 is the stop mechanism and 17 the brake. 18 is a dog fast to a rock shaft 19, which when rocked

2
releases an arm 20 and allows the stop mechanism to operate to throw the clutch member 13 out of engagement with the clutch pulley 12 and to operate the brake 17 to stop the machine. 21 and 22 are rotary shafts to which are fastened toothed disks 23 and 24, which constitute rotary stop members. 25 and 26 are normally stationary stop members comprising bars extending longitudinally of the machine and arranged to slide thereon. 27 and 28 are rock shafts having arms 29 and 30 respectively fastened thereto and said arms being connected together by a connecting link 31.

15 The mechanism hereinbefore specifically described is substantially the same as disclosed in said Letters Patent.

The normally stationary stop 25 is moved toward and away from the rotary stop member 23 by an arm 32 which is fastened to the arm 29 and projects upwardly therefrom into a slot 33 extending longitudinally along the underside of the normally stationary stop 25. The arm 29 has an upward extension 34 thereon which has adjustably attached thereto an arm 35 which has a counterweight 36 adjustably fastened thereon. A link 37 is pivoted at 38 to the upper end of the arm 34 and its free end projects 30 through a slot 39 provided in a stop plate 40. Said link is provided in its upper edge with a notch 41 into which the upper edge of said slot 39 projects. Said link 37 is held in the position illustrated in Fig. 2 by a 35 spring 42. An arm 43 fast to the rock shaft 14 is adapted to engage the upper edge of the link 37, when the stop motion mechanism is operated, to throw the link 37 downwardly out of engagement with the upper edge of the slot 39, whereupon the arm 35 will cause the arm 34 to be tipped from the position illustrated in full lines to the position shown in dotted lines Fig. 2, thus through the arm 32 causing the normally 45 stationary stop member 25 to be moved out of operative position relatively to the rotary stop member 23. The arm 43 is operated to engage the upper edge of the link 37, as hereinbefore described, by the rocking of 50 the rock shaft 14 to which it is fastened, and the rock shaft 14 is operated in the same manner as the rock shaft 30 described in said Letters Patent No. 1,173,244, page 2, lines 58 to 82 inclusive. It is evident that a 55 spring may be used to move the arm 34 from the position shown in full lines to that shown in dotted lines, instead of employing the weighted arm 35, without departing from the spirit of my invention.

60 A handle 14' fastened to the rock shaft 14 enables said rock shaft to be manually operated when desired. The rock shaft 27 may be manually operated when desired by means of the extension arm 34.

65 An arm 44 is fastened to the rock shaft

28 and has a pin 45 extending upwardly therefrom into a slot 46 which slot extends longitudinally along the underside of the normally stationary stop 26 and by this means said normally stationary stop 26 may 70 be moved toward and away from the rotary stop members 24 through the medium of the connecting link 31 and arm 30. Each of the normally stationary stop members 25 and 26 is provided with two series of oppositely 75 disposed brackets 47 and 48, see Figs. 3, 4 and 5, which are fast to their respective normally stationary stops.

Referring to Figs. 3, 4 and 5, the bracket 47 has a rock shaft 49 pivotally mounted thereon and at one end of said shaft an arm 50 is fast thereto and projects upwardly and laterally at 51 to receive a yarn guide 52. This arm is provided with a slidably adjustable weight 53 which is held in adjusted position by a spring 54, Fig. 6. A stationary yarn guide 55 is positioned above the yarn guide 52 and is fastened to the bracket 47. Another yarn guide 56 is positioned below the yarn guide 52 and is mounted upon a bracket 57 which is adjustably fastened to the bracket 47, so that the yarn guide 56 can be adjusted toward and away from the yarn guide 52 to increase or diminish respectively the tension upon the yarn 58, which yarn extends from a bobbin 59, Figure 1, through a stationary yarn guide 60 fast to the frame of the machine, through the yarn guides 56, 52 and 55 and thence passes to the machine where it is guided to the needles in the usual manner. The arm 50 is normally, that is when the yarn is passing through the yarn guide 52 under tension during the operation of the machine, positioned at a slight angle to a vertical plane containing the axis of the rock shaft 49. It is prevented from assuming at any time a vertical position by abutting against the bracket 57, so that when the yarn 58 breaks the arm 50 and yarn guide 52 will tip from the position shown in full lines, Fig. 5, to the position shown in dotted lines inclined toward the right in said figure and with a locking arm 61 fast to or forming a part of the rock shaft 49 100 abutting against the normally stationary stop 25.

As will be seen by reference to Figs. 3, 4 and 5, when the arm 61 is in its elevated position as shown in full lines in said figures, it will be out of the path of the rotary stop member 23 and at that time the yarn guide will be in the position illustrated in full lines Fig. 5, and the yarn will be passing therethrough under tension.

When the yarn breaks the yarn guide 52 and its arm 50, with the counterweight 53 being located in a plane slightly inclined toward the right, Fig. 5, from a vertical plane, said yarn guide and its arm will drop to 105

the position illustrated in Fig. 5 in dotted lines, and the arm 61 will abut against the normally stationary stop 25 and the rotary stop member 23 will engage said arm 61, the 5 arm 61 then acting as a locking means which stops the rotation of the rotary stops 23 and the shafts 21 to which they are fastened. When this occurs the stop mechanism of the machine will be operated to throw out 10 the clutch and stop the machine, as set forth in said Letters Patent No. 1,173,244.

Any tendency to bend the arm 61 rearwardly is prevented by a vertical pin 62 fast to and projecting upwardly from the normally stationary stop 25. When the normally stationary stop 25 is moved rearwardly, that is to the right in Fig. 3, the rocking arm 61 engages the inclined edge 63 of a cam plate 64 which is fastened to a 15 stationary bar 65, which in turn is fastened by brackets 66 to the frame of the machine, and as said arm 61 engages the inclined edge 63 during the rearward motion of the normally stationary stop 25, upon which it is 20 mounted, the arm 61 will be tipped upwardly and the rock shaft 49 with the arm 50 and yarn guide 52 will be moved toward and approximately to the position illustrated in full lines, Fig. 5, but there will be a certain 25 amount of play allowed for the yarn guide 52 from the position where the arm 50 strikes the bracket 57 to the position where the arm 61 strikes the upper edge of the plate 64, so that when the yarn first starts to take up 30 its slack motion and finally in the operation of the machine the tension on the yarn becomes normal.

The yarn guide 52 only has to be moved a very slight distance in order to position 40 it as shown in full lines, Fig. 5, and the strain on the yarn, necessitated by moving the yarn guide 52 to this position, is very slight on account of the position of the arm 50 which is slightly inclined, as hereinbefore 45 set forth, to a vertical plane.

The yarn 58', Fig. 4, is led from a bobbin 59', Fig. 1, through yarn guides 60', 56', 52', 55' to the needles of the machine, the yarn guide 52' being supported upon an arm 50' 50 which extends upwardly from a rock shaft 49' pivotally mounted in the bracket 48 and provided at the opposite end thereof from that to which the arm 50 is attached with a laterally extending arm 61' which is adapted 55 to be engaged by one of the rotary stop members 23 and also is adapted to be engaged when the normally stationary stop 25 is moved rearwardly, by the inclined edge 63' of a plate 64' fastened to the stationary bar 65.

The operation of the yarn guide 52' and its associated parts is the same as that of the yarn guide 52 hereinbefore described, the only difference being that the arm 61' projects in the opposite direction from that in

which the arm 61 projects and the arm 61' engages the plate 64' instead of the plate 64.

The yarn guides on the opposite side of the machine, which are operated in connection with the rotary stops 24 and the normally stationary stops 26, are the same as hereinbefore described with relation to the 70 yarn guides for the rotary stops 23 and normally stationary stops 25.

The number of bobbins and the number of 75 yarn guides and rotary stops may be increased as desired and all will operate as hereinbefore described.

An alarm device is provided in this machine and is substantially the same as the 80 alarm device shown and described in said Letters Patent No. 1,186,645 and consists of an arm 67 which engages a spring 68 to hold said spring out of engagement with one of the rotary members 23 when the stationary stop member is in its forward position and the arm 67 is fast to the rock shaft 27 and is tipped thereby to allow the spring clicker 68 to engage one of the rotary members 23 when the normally stationary stop member 25 is thrown back.

The general operation of the mechanism which has been specifically and to some extent in general described is as follows:— Assuming the machine to be in operation and the parts to be in the relative positions illustrated in the figures of the drawings, if a thread slackens or breaks, or if, for any reason, the normal and proper operation of the machine in respect to the feeding of the 90 yarn is interfered with, the yarn guide 52 or 52', through which the yarn passes which is not operating properly, or which has become broken, immediately drops from the position illustrated in full lines Fig. 5 to the 95 position illustrated in dotted lines therein, whereupon the locking arm 61 or 61', as the case may be, drops to the position illustrated in dotted lines in said figure and is engaged by its respective rotary member 23 and by 100 the normally stationary member 25, whereupon the rotation of the shaft 21 will be stopped and through suitable mechanism will operate the stop mechanism 16 in the same manner as set forth in said Letters Patent 105 No. 1,173,244 to throw the clutch member 13 out of operative engagement with the clutch pulley 12 and the brake 17 will be set to stop the machine. During the latter part 110 of this stopping operation the rock shaft 14 will cause the rocker arm 43 to engage the link 37 as hereinbefore set forth and move the same downwardly so that the weighted arm 35 will cause said link 37 to be moved from the position illustrated in full lines to

that illustrated in dotted lines, Fig. 2, the arm 35 assuming the position illustrated in dotted lines in said figure. This will cause the normally stationary stop members 25 and 26 with their respective brackets 47 115 120 125 130

and 48 and their yarn guides 56, 56', 52, 52', 55 and 55' and all other instrumentalities mounted on said normally stationary stop members to be moved out of operative position relatively to their respective rotary stop members, as hereinbefore described. At the same time the clicker 68 will be thrown into engagement with the teeth of the rotary stop member 23 and operates as set forth in said 10 Letters Patent No. 1,186,645. As the normally stationary stop member is moved away from the rotary stop members, the arms 61 and 61' ride upon the inclines 63 and 63' on their respective plates 64 and 64' 15 and the yarn guide 52 is brought into position to be rethreaded, that is, into a position approximately that illustrated in full lines in Fig. 5 in which position the yarn guide 52 can be moved toward the left, Fig. 20 5, until the arm 50 strikes the bracket 57 and toward the right until the arm 61 engages the upper edge of the plate 64. After the difficulty which has caused the machine to stop has been remedied, the operator 25 releases the brake and sets the stop motion in the position shown in Fig. 1. He then throws the clutch in and the machine starts, and as soon as the tension on the yarn has 30 become sufficient to cause said arms to pick up the different yarn guides 56 and 56' and move them slightly toward a vertical plane and into the position illustrated in Fig. 5 in full lines and the operator is warned by the clicker 68 snapping over the teeth of one 35 of the rotary stop members that the stationary stop members are out of position, he throws the stationary stop members into position by means of the extension arm 34, or by means of any conveniently positioned 40 handle not shown in the drawings whichever may be the most convenient. This action moves the link 37 to the position illustrated in full lines, Fig. 2, and held up against the stop plate 40 with the notch 41 in 45 engagement therewith by the spring 42. The machine is then in operative position in every respect and the stop motion set ready to detect any other flaw that may appear in the yarn or any difficulty that may 50 develop in the feeding of said yarn.

It will be understood that if the operator wishes to stop the machine for any reason such for instance as to replace a broken needle, examine the fabric, put in a new bobbin, 55 etc., he can throw the clutch member 13 out by means of the handle 14' and the machine will then stop of its own inertia without using the brake or actuating the stop mechanism, but the normally stationary stop 60 members will be thrown out because the arm 43 will engage the link 37 and allow the weighted arm 35 to throw the arm 32 back and the normally stationary stop member 65 will be moved back out of operative position. The resulting advantage being that

the operator can turn the machine by hand as he may desire without having to turn it against the friction of the brake and furthermore, when the machine is again started the operator does not have to release the 70 brake and set the stop again but can throw in the clutch and immediately start the machine in operation, and then when the yarns have picked up their respective yarn guides he moves the normally stationary stop 75 members forward into operative position and said normally stationary stop members become automatically locked in position by the arm 34 and link 37.

It will further be understood that in 80 every case, whether the machine is stopped automatically or by hand, that the dropping of the yarn guides from the position shown in full lines, Fig. 5, to that shown in dotted lines and the stopping of the machine occurs 85 before the normally stationary stops are moved out of operation and then just as the machine is stopped the normally stationary stops are operated to throw the same out of 90 operative position and the yarn guides are positioned substantially in the position illustrated in full lines, Fig. 5, and ready to be positioned as shown in Fig. 5 in full lines by the yarns when the machine is again started.

I claim:

1. A stop motion mechanism for a knitting machine having, in combination, a driving shaft, a rotary stop member, a normally stationary stop member adjacent thereto, a 100 guide for a strand of yarn, a pivotally mounted member to which said yarn guide is attached, locking means actuated by said pivotally mounted member and normally held out of engagement with said stop members by said strand of yarn when under tension during the operation of said knitting machine, said locking means being adapted to be moved by said pivotally mounted member into interlocking engagement with said 105 stops when allowed by said yarn so to do, whereby the rotation of said rotary stop member may be stopped, and mechanism actuated by the stopping of said rotary stop member constructed and arranged to stop 110 the rotation of said shaft.

2. A stop motion mechanism for a knitting machine having, in combination, a driving shaft, a rotary stop member, a normally stationary stop member adjacent thereto, a 120 rock shaft, a guide for a strand of yarn mounted on said rock shaft, locking means actuated by said rock shaft and normally held out of engagement with said stop members by said strand of yarn when under tension during the operation of said knitting machine, said locking means being adapted to be moved by said rock shaft into 125 interlocking engagement with said stops when allowed by said yarn so to do, whereby 130

the rotation of said rotary stop member may be stopped, and mechanism actuated by the stopping of said rotary stop member constructed and arranged to stop the rotation 5 of said driving shaft.

3. A stop motion mechanism for a knitting machine having, in combination, a driving shaft, a rotary stop member, a normally stationary stop member adjacent thereto, a 10 rock shaft, a guide for a strand of yarn mounted on said rock shaft, an arm on said rock shaft constituting a locking means and normally held out of engagement with said stop members by said strand of yarn when 15 under tension during the operation of said knitting machine, said arm being adapted to be moved by said rock shaft into interlocking engagement with said stops when allowed by said yarn so to do, whereby the 20 rotation of said rotary stop member may be stopped and mechanism actuated by the stopping of said rotary stop member constructed and arranged to stop the rotation of said driving shaft.

25 4. A stop motion mechanism for a knitting machine having, in combination, a driving shaft, a rotary stop member, a normally stationary stop member adjacent thereto, a rock shaft, a pair of arms on said rock shaft, a 30 guide for a strand of yarn on one of said arms, the other of said arms constituting a locking means and normally held out of engagement with said stop members by said strand of yarn when under tension during 35 the operation of said knitting machine, said locking means being adapted to be rocked by said rock shaft into interlocking engagement with said stops when allowed by said yarn so to do, whereby the rotation of said rotary 40 stop member may be stopped, and mechanism actuated by the stopping of said rotary stop member constructed and arranged to stop the rotation of said driving shaft.

45 5. A stop motion mechanism for a knitting machine having, in combination, a driving shaft, a rotary stop member, a normally stationary stop member adjacent thereto, a rock shaft, an arm on said rock shaft, a yarn 50 guide for a strand of yarn on said arm, said arm adapted to be positioned at a slight angle to a vertical plane containing the axial line of said rock shaft, another arm on said rock shaft constituting a locking means and normally held out of engagement with said 55 stop members by said strand of yarn when under tension during the operation of said knitting machine, said locking means being adapted to be moved by said rock shaft into interlocking engagement with said stops 60 when allowed by said yarn so to do, whereby the rotation of said rotary stop member may be stopped, and mechanism actuated by the stopping of said rotary stop member constructed and arranged to stop the rotation of said driving shaft.

6. A stop motion mechanism for a knitting machine having, in combination, a driving shaft, a rotary stop member, a normally stationary stop member adjacent thereto, a rock shaft, an arm on said rock shaft, a 70 guide for a strand of yarn on said arm, locking means on said rock shaft and normally held out of engagement with said stop members by said strand of yarn when under tension during the operation of said 75 knitting machine, said locking means being adapted to be moved by said rock shaft into interlocking engagement with said stops when allowed by said yarn so to do, whereby the rotation of said rotary stop member 80 may be stopped, a pair of oppositely disposed yarn guides located on opposite sides respectively of said rocker arm yarn guide, and mechanism actuated by the stopping of said 85 rotary stop member constructed and arranged to stop the rotation of said driving shaft.

7. A stop motion mechanism for a knitting machine having, in combination, a 90 driving shaft, a rotary stop member, a normally stationary stop member adjacent thereto, a rock shaft, an arm on said rock shaft, a guide for a strand of yarn on said arm, locking means on said rock shaft and normally held out of engagement with said 95 stop members by said strand of yarn when under tension during the operation of said knitting machine, said locking means being adapted to be moved by said rock shaft into interlocking engagement with said stops 100 when allowed by said yarn so to do, whereby the rotation of said rotary stop member may be stopped, said yarn guide arm being normally positioned by said yarn when under tension during the operation of said 105 knitting machine at an angle containing the axial line of said rock shaft, adjustable means adapted to engage said arm and prevent its assuming a vertical position, and mechanism actuated by the stopping of said 110 rotary stop member constructed and arranged to stop the rotation of said driving shaft.

8. A stop motion mechanism for a knitting machine having, in combination, a driving shaft, a rotary stop member, a normally stationary stop member adjacent thereto, a rock shaft, an arm on said rock shaft, a guide for a strand of yarn on said arm, locking means on said rock shaft and normally held out of engagement with said 115 stop members by said strand of yarn when under tension during the operation of said knitting machine, said locking means being adapted to be moved by said rock shaft into interlocking engagement with said stops when allowed by said yarn so to do, whereby the rotation of said rotary stop member 120 may be stopped, a pair of oppositely disposed yarn guides located on opposite sides 125 when allowed by said yarn so to do, whereby the rotation of said rotary stop member may be stopped, a pair of oppositely disposed yarn guides located on opposite sides 130

respectively of said rocker arm yarn guide, one of said yarn guides being adjustable toward and away from the other, whereby the tension on said yarn may be adjusted, and 5 mechanism actuated by the stopping of said rotary stop member constructed and arranged to stop the rotation of said driving shaft.

9. A stop motion mechanism for a knitting machine having, in combination, a driving shaft, a rotary stop member, a normally stationary stop member, means constructed and arranged to move said stationary stop member out of operative position 10 relatively to said rotary stop member, means to lock said stationary stop member in operative position relatively to said rotary stop member, a guide for a strand of yarn, a pivotally mounted member mounted on said 15 stationary stop member to which pivotally mounted member said yarn guide is attached, locking means on said normally stationary stop member actuated by said pivotally mounted member and normally held 20 out of engagement with said stop members by said strand of yarn when under tension during the operation of said knitting machine, said second-named locking means being adapted to be moved by said pivotally 25 mounted member into interlocking engagement with said stops when allowed by said yarn so to do, whereby the rotation of said rotary stop member may be stopped, mechanism actuated by the stopping of said rotary 30 stop member constructed and arranged to stop the rotation of said driving shaft and means to operate said first-named locking 35 means to release said stationary stop member and allow the same to be moved out of 40 operative position.

10. A stop motion mechanism for knitting machines having, in combination, a driving shaft, a plurality of rotary stop members, a normally stationary stop member adjacent thereto common to all of said rotary stop members and movable toward and away from said rotary stop members, a plurality of guides for strands of yarn, a pivotally mounted member for each of said 45 yarn guides, locking means on each of said pivotally mounted members normally held out of engagement with said stop members by its respective strand of yarn when under tension during the operation of said knitting machine, said locking means being 50 adapted to be moved by its respective pivotally mounted member into interlocking engagement with one of said rotary stops and said normally stationary stop when allowed by its respective strand of yarn so to 55 do, whereby the rotation of said rotary stop members may be stopped while said normally stationary stop member is stationary and mechanism actuated by the stopping of 60 said rotary stop members constructed and 65

arranged to stop the rotation of said driving shaft.

11. A stop motion mechanism for knitting machines having, in combination, a driving shaft, a driven member constituting a stop, 70 a normally stationary stop member adjacent thereto and movable toward and away from said driven member, a pivotally mounted member, a guide for a strand of yarn mounted on said pivotally mounted member, locking means actuated by said pivotally mounted member and normally held out of engagement with said stop members by said strand of yarn when under tension during the operation of said knitting machine, said locking 75 means being adapted to be moved by said pivotally mounted member into interlocking engagement with said stops when allowed by said yarn so to do, whereby the rotation of said rotary stop member may be 80 stopped and mechanism actuated by the stopping of said rotary stop member, constructed and arranged to stop the rotation of said shaft.

12. A stop motion mechanism for a knitting machine having, in combination, a driving shaft, a rotary stop member, a normally stationary stop member adjacent thereto, a guide for a strand of yarn, a pivotally mounted member to which said yarn guide is attached, locking means actuated by said pivotally mounted member and normally held out of interlocking engagement with said stop members by said strand of yarn 95 when under tension during the operation of said knitting machine, said locking means being adapted to be moved by said pivotally mounted member into interlocking engagement with said stops when allowed by said yarn so to do, whereby the rotation of said rotary stop member may be stopped, mechanism actuated by the stopping of said rotary stop member constructed and arranged to stop the rotation of said shaft and move said locking means out of interlocking 100 engagement with said stop members.

13. A stop motion mechanism for a knitting machine having, in combination, a driving shaft, a rotary stop member, a normally stationary stop member adjacent thereto, a guide for a strand of yarn, a pivotally mounted member to which said yarn guide is attached, locking means actuated by said pivotally mounted member and normally held out of interlocking engagement with said stop members by said strand of yarn 115 when under tension during the operation of said knitting machine, said locking means being adapted to be moved by said pivotally mounted member into interlocking engagement with said stops when allowed by said yarn so to do, whereby the rotation of said rotary stop member may be stopped, and mechanism actuated by the stopping of said rotary stop member constructed and arranged to stop the rotation of said shaft and move said locking means out of interlocking 120 engagement with said stop members.

125

ranged to stop the rotation of said shaft and move said locking means out of interlocking engagement with said stop members and said yarn guide into operative position.

- 5 14. A stop motion mechanism for a knitting machine having, in combination, a driving shaft, a rotary stop member, a normally stationary stop member adjacent thereto, a rock shaft, a guide for a strand of yarn mounted on said rock shaft, locking means actuated by said rock shaft and normally held out of interlocking engagement with said stop members by said strand of yarn when under tension during the operation of 10 said knitting machine, said locking means being adapted to be moved by said rock shaft into interlocking engagement with said stops when allowed by said yarn so to do, whereby the rotation of said rotary stop member may be stopped, and mechanism actuated by the stopping of said rotary stop member constructed and arranged to stop the rotation of said driving shaft, and move 15 said locking means out of interlocking engagement with said stop members.

- 15 15. A stop motion mechanism for a knitting machine having, in combination, a driving shaft, a rotary stop member, a normally stationary stop member adjacent thereto, a rock shaft, a guide for a strand of yarn mounted on said rock shaft, locking means actuated by said rock shaft and normally held out of interlocking engagement with said stop members by said strand of 20 yarn when under tension during the operation of said knitting machine, said locking means being adapted to be moved by said rock shaft into interlocking engagement with said stops when allowed by said yarn so to do, whereby the rotation of said rotary stop member may be stopped, and mechanism actuated by the stopping of said rotary stop member constructed and arranged to stop the rotation of said driving shaft and move 25 said locking means out of interlocking engagement with said stop members and said yarn guide into operative position.

- 25 16. A stop motion mechanism for a knitting machine having, in combination, a driving shaft, a rotary stop member, a normally stationary stop member adjacent thereto, a rock shaft, a guide for a strand of yarn mounted on said rock shaft, locking means actuated by said rock shaft and normally held out of interlocking engagement with said stop members by said strand of 30 yarn when under tension during the operation of said knitting machine, said locking means being adapted to be moved by said rock shaft into interlocking engagement with said stops when allowed by said yarn so to do, whereby the rotation of said rotary stop member may be stopped, and mechanism actuated by the stopping of said rotary stop member constructed and arranged to stop the rotation of said driving shaft and move 35 said locking means out of interlocking engagement with said stop members and said yarn guide into operative position.

- 35 17. A stop motion mechanism for a knitting machine having, in combination, a driving shaft, a rotary stop member, a normally stationary stop member adjacent thereto, a rock shaft, a guide for a strand of yarn mounted on said rock shaft, an arm on said rock shaft constituting a locking means and normally held out of interlocking engagement with said stop members by said strand of yarn when under tension during the operation of said knitting machine, said arm being adapted to be moved by said 40 rock shaft into interlocking engagement with said stops when allowed by said yarn so to do, whereby the rotation of said rotary stop member may be stopped and mechanism actuated by the stopping of said rotary stop member constructed and arranged to stop the rotation of said driving shaft and move 45 said locking means out of interlocking engagement with said stop members and said yarn guide into operative position.

to stop the rotation of said driving shaft and move said arm out of interlocking engagement with said stop members.

17. A stop motion mechanism for a knitting machine having, in combination, a driving shaft, a rotary stop member, a normally stationary stop member adjacent thereto, a rock shaft, a guide for a strand of yarn mounted on said rock shaft, an arm on said rock shaft constituting a locking means and normally held out of interlocking engagement with said stop members by said strand of yarn when under tension during the operation of said knitting machine, said arm being adapted to be moved by said rock shaft into interlocking engagement with said stops when allowed by said yarn so to do, whereby the rotation of said rotary stop member may be stopped and mechanism actuated by the stopping of said rotary stop member constructed and arranged to stop the rotation of said driving shaft and move said arm out of interlocking engagement with said stop members and said yarn guide into operative position.

18. A stop motion mechanism for a knitting machine having, in combination, a driving shaft, a rotary stop member, a normally stationary stop member adjacent thereto, a rock shaft, a pair of arms on said rock shaft, a guide for a strand of yarn on one of said arms, the other of said arms constituting a locking means and normally held out of interlocking engagement with said stop members by said strand of yarn when under tension during the operation of said knitting machine, said locking means being adapted to be rocked by said rock shaft into interlocking engagement with said stops when allowed by said yarn so to do, whereby the rotation of said rotary stop member may be stopped, and mechanism actuated by the stopping of said rotary stop member constructed and arranged to stop the rotation of said driving shaft and move said arm which constitutes a locking means out of interlocking engagement with said stop members.

19. A stop motion mechanism for a knitting machine having, in combination, a driving shaft, a rotary stop member, a normally stationary stop member adjacent thereto, a rock shaft, a pair of arms on said rock shaft, a guide for a strand of yarn on one of said arms, the other of said arms constituting a locking means and normally held out of interlocking engagement with said stop members by said strand of yarn when under tension during the operation of said knitting machine, said locking means being adapted to be rocked by said rock shaft into interlocking engagement with said stops when allowed by said yarn so to do, whereby the rotation of said rotary stop member may be stopped, and mechanism actuated by

the stopping of said rotary stop member constructed and arranged to stop the rotation of said driving shaft and move said arm which constitutes a locking means out 5 of interlocking engagement with said stop members and said yarn guide into operative position.

20. A stop motion mechanism for a knitting machine having, in combination, a 10 driving shaft, a rotary stop member, a normally stationary stop member adjacent thereto, a rock shaft, an arm on said rock shaft, a yarn guide for a strand of yarn on said arm, said arm adapted to be positioned 15 at a slight angle to a vertical plane containing the axial line of said rock shaft, another arm on said rock shaft constituting a locking means and normally held out of interlocking engagement with said stop members by 20 said strand of yarn when under tension during the operation of said knitting machine, said locking means being adapted to be moved by said rock shaft into interlocking engagement with said stops 25 when allowed by said yarn so to do, whereby the rotation of said rotary stop member may be stopped, and mechanism actuated by the stopping of said rotary stop member constructed and arranged to stop the rotation 30 of said driving shaft and move said arm constituting a locking means out of interlocking engagement with said stop members.

21. A stop motion mechanism for a knitting machine having, in combination, a driving shaft, a rotary stop member, a normally stationary stop member adjacent thereto, a rock shaft, an arm on said rock shaft, a 35 yarn guide for a strand of yarn on said arm, said arm adapted to be positioned at a slight angle to a vertical plane containing the axial line of said rock shaft, another arm on said rock shaft constituting a locking means and normally held out of interlocking 40 engagement with said stop members by said strand of yarn when under tension during the operation of said knitting machine, said locking means being adapted to be moved by said rock shaft into interlocking 45 engagement with said stops when allowed by said yarn so to do, whereby the rotation of said rotary stop member may be stopped, and mechanism actuated by the stopping of 50 said rotary stop member constructed and arranged to stop the rotation of said driving shaft and move said arm constituting a locking means out of interlocking engagement with said stop members and said yarn 55 guide into operative position.

60. 22. A stop motion mechanism for a knitting machine having, in combination, a driving shaft, a rotary stop member, a normally stationary stop member, means constructed and arranged to move said stationary stop 65 member out of operative position relatively

to said rotary stop member, means to lock said stationary stop member in operative position relatively to said rotary stop member, a guide for a strand of yarn, a pivotally mounted member mounted on said stationary stop member to which pivotally mounted member said yarn guide is attached, locking means on said normally stationary stop member actuated by said pivotally mounted member and normally held out of 70 interlocking engagement with said stop members by said strand of yarn when under tension during the operation of said knitting machine, said second-named locking means being adapted to be moved by said pivotally mounted member into interlocking engagement with said stops when allowed by said yarn so to do, whereby the rotation of said rotary stop member may be stopped, mechanism actuated by the stopping of said 75 rotary stop member constructed and arranged to stop the rotation of said driving shaft and means to operate said first-named locking means to release said stationary stop member and allow the same to 80 be moved out of operative position together with said second-named locking means, whereby said second-named locking means may be moved out of interlocking engagement with said stop members. 85

23. A stop motion mechanism for a knitting machine having, in combination, a driving shaft, a rotary stop member, a normally stationary stop member, means constructed and arranged to move said stationary stop member out of operative position relatively to said rotary stop member, means to lock said stationary stop member in operative position relatively to said rotary stop member, a guide for a strand of yarn, a pivotally mounted member mounted on said stationary stop member to which pivotally mounted member said yarn guide is attached, locking means on said normally stationary stop member actuated by said pivotally mounted member and normally held out of 100 interlocking engagement with said stop members by said strand of yarn when under tension during the operation of said knitting machine, said second-named locking means being adapted to be moved by said pivotally mounted member into interlocking engagement with said stops when allowed by said yarn so to do, whereby the rotation of said rotary stop member may be stopped, mechanism actuated by the stopping of said rotary stop member constructed and arranged to stop the rotation of said driving shaft and means to operate 105 said first-named locking means to release said stationary stop member and allow the same to be moved out of operative position together with said second-named locking means whereby said second-named locking means may be moved out of interlocking engagement with said stop members. 110

gagement with said stop members, and means adapted to be engaged by said second-named locking means to move said yarn guide into operative position.

5 24. A stop motion mechanism for a knitting machine having, in combination, a driving shaft, a rotary stop member, a normally stationary stop member, a guide for a strand of yarn, locking means normally held out of 10 interlocking engagement with said stop members by said strand of yarn when under tension during the operation of said knitting machine, said locking means being adapted to be moved into interlocking engagement with said stops when allowed by said yarn so to do, whereby the rotation of said rotary stop member may be stopped, mechanism actuated by the stopping of said rotary stop member constructed and arranged to stop 15 the rotation of said driving shaft, said mechanism embodying means to move said stationary stop member and said arm which constitutes a locking means away from said rotary stop member and out of interlocking engagement with said stop members and means adapted to engage said arm when said normally stationary stop member is being moved away from said rotary stop member and rock said shaft to move said 20 50 55 yarn guide into operative position.

25 25. A stop motion mechanism for a knitting machine having, in combination, a driving shaft, a rotary stop member, a normally stationary stop member adjacent thereto, a rock shaft, a guide for a strand of yarn member and stationary means adapted to engage said locking means and move said yarn guide into operative position.

30 25. A stop motion mechanism for a knitting machine having, in combination, a driving shaft, a rotary stop member, a normally stationary stop member adjacent thereto, a rock shaft, a guide for a strand of yarn

mounted on said rock shaft, an arm on said rock shaft constituting a locking means and normally held out of interlocking engagement with said stop members by said strand of yarn when under tension during the operation of said knitting machine, said arm being adapted to be moved by said rock shaft into interlocking engagement with 40 said stops when allowed by said yarn so to do, whereby the rotation of said rotary stop member may be stopped and mechanism actuated by the stopping of said rotary stop member constructed and arranged to stop 45 the rotation of said driving shaft, said mechanism embodying means to move said stationary stop member and said arm which constitutes a locking means away from said rotary stop member and out of interlocking engagement with said stop members and means adapted to engage said arm when said normally stationary stop member is being moved away from said rotary stop member and rock said shaft to move said 50 55 yarn guide into operative position.

In testimony whereof I have hereunto set my hand in presence of two subscribing witnesses.

WILLIAM T. BARRATT.
